UNITED STATES PATENT OFFICE.

ROBERT Y. BARROWS, OF RUTHERFORD, NEW JERSEY, ASSIGNOR, BY DIRECT AND MESNE ASSIGNMENTS, OF ONE-HALF TO GEORGE H. HARMAN, INC., A CORPORATION OF NEW JERSEY, AND ONE-HALF TO ROBERT Y. BARROWS, INC., A CORPORATION OF NEW YORK.

POWDER AND ROUGE CONTAINER.

1,385,856.

Specification of Letters Patent.

Patented July 26, 1921.

Application filed August 13, 1920. Serial No. 403,383.

To all whom it may concern:

Be it known that I, ROBERT Y. BARROWS, a citizen of the United States, residing at Rutherford, in the county of Bergen and State of New Jersey, have invented certain new and useful Improvements in Powder and Rouge Containers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in cases or containers adapted to hold face-powders, cosmetics, and the like; and, the invention has reference, more particularly, to a novel construction of case or container adapted to hold powders and rouge in the form of compacts or cakes, as, for example, one compact comprising white face powder and the other pink or red rouge, said compacts or cakes being supported centrally in a vertical position and back to back, so that intermediate the face of each compact and the opposite wall of the case or container there is provided a storage space for a puff, thus providing, in a very neat and attractive form, a double compartment case or container.

The invention has, therefore, for its principal object to provide a very simple and attractive vertical double compact combination case or container of small bulk, having means for supporting two compacts, one of which is composed of white face powder and the other of pink or red rouge, in such novel relation to the interior of the case or container, that the same are securely held in a central vertical position back to back within the case, and in such spaced relation from the sides of the case or container as to provide a separate compartment adjacent to the face of each compact for the reception of the puffs serving the respective compacts.

Other objects of the present invention, not at this time more particularly enumerated, will be clearly understood from the following detailed description of the same.

With the various objects of the invention

in view, the same consists, primarily, in the novel construction of vertical double compact case or container hereinafter set forth; and, the invention consists, furthermore, in the novel arrangements and combinations of the various devices and parts, as well as in the details of the construction of said parts, all of which will be more fully described in the following specification, and then finally embodied in the claims appended thereto.

The invention is clearly illustrated in the accompanying drawings, in which:

Figure 1 is an exterior or face view of one form of the case or container embodying the principles of my present invention; Fig. 2 is an edge or side view of the same, the opened position of the cover portion being indicated in dotted outline; Fig. 3 is a vertical longitudinal section, taken on line 3-3 in said Fig. 2; Fig. 4 is a vertical longitudinal cross-section, taken on line 4-4 in said Fig. 1; Fig. 5 is a top view of the case or container with the cover portion open, said cover portion being partially broken away; and Fig. 6 is a horizontal cross-section, taken on line 6-6 in said Fig. 3.

Fig. 7 is a top view, with cover portion open, of a somewhat modified form of my novel case or container, which embodies, however, the general principles of my invention; Fig. 8 is a vertical longitudinal section through the same with the cover closed; Fig. 9 is a vertical longitudinal cross-section, taken on line 9-9 in said Fig. 8; and Fig. 10 is a perspective view of a combined compact retaining means and holding device for stick cosmetics, which is employed in the said modified form of my novel case or container.

Similar characters of reference are employed in all of the hereinabove described views to indicate corresponding parts.

Referring now to Figs. 1 to 6 inclusive of the drawings, I have illustrated therein one embodiment of my novel case or container, comprising a main body or shell 1 which may be variously formed to produce the desired ornamental exterior contour or shape. The end walls of said body or shell 1 are provided with vertically disposed outwardly pressed ribs 2, which are centrally positioned intermediate the side walls of the body or shell, thus providing in the inner

faces of said end walls vertical receiving grooves or channels 3. The upper ends of said ribs 2 terminate short of the margin of the open end of said body or shell, and are thereby arranged to provide a shoulder or stop-portion 4 at the upper end or extremity of each groove or channel 3. The margin of the open end of said body or shell 1 is formed to provide an inwardly off-set cover engaging bezel 5. Secured to the open end of said body or shell 1, by means of a suitable hinge connection 6, is a cover member 7, which, when closed, engages telescopically over the above mentioned bezel 5. Arranged within said cover member 7, and seated against the inner side of the top wall thereof is a mirror member 8, the same being retained in place by a retaining ring 9 which is engaged in an internal groove 10 provided by an annular bead 10' formed in said cover member.

The compacts to be retained within the body or shell 1 comprise, a face powder compact 11 and a rouge compact 12. Each compact 11 and 12 is preferably circular in form with a flat back and convex face. In mounting the compacts within the body or shell, the same are placed back to back, and are then inserted within the interior of the body or shell with opposite points of their marginal edges 13 entered within the embrace of said grooves or channels 3 (as shown more particularly in Fig. 6 of the drawings). The lower edges of said compacts may rest upon the bottom of the body or shell, unless (as shown in the drawings) the body or shell tapers toward its lower ends, in which case engagement with the inwardly inclined grooves or channels 3 will adequately support the same. When thus arranged within the body or shell 1, the compacts 11 and 12 are supported in a central vertical position, so that a puff-receiving space or compartment 14 is provided intermediate the convex face of each compact and the opposite wall of the container or case. In order to prevent displacement of the compacts 11 and 12 from their above described central vertical disposition within the body or shell 1, I provide an arcuate retaining yoke 15, the main body of which is concavo-convex in cross-section, so that the same may be caused to embrace the upper portions of the margins of the compacts (as shown more clearly in Figs. 3, 4 and 5 of the drawings). The free ends 16 of said retaining yoke 15 are upwardly curved, and are adapted to be sprung respectively beneath the respective shoulders or stop-positions 4 at the upper ends of the grooves or channels 3, and when so engaged are placed under sufficient tension to firmly hold the yoke 15 in engaged relation to the compacts, as well as against displacement from its retaining relation thereto. Placed in the re-

spective compartments 14 are the puffs 17 and 18, one serving to coöperate with the face powder compact 11 and the other with the rouge compact 12. In utilizing the device, the user opens the cover-member 7, and 70 grasping the puff desired, withdraws the same from its compartment thereby causing the same to frictionally pass over the face of the compact which it serves so that some of the material of the compact is thereby 75 transferred to the puff face for application by means of the puff to the person of the user.

From the above description it will be evident that my novel case providing for the 80 mounting and retaining of the compacts in vertical position makes for a considerable reduction in the bulk of the case, while at the same time rendering the case itself subject to a wide range of variation in shape 85 and design, thus permitting the embodiment therein of a variety of ornamental effects which greatly enhance the distinctiveness and attractiveness of the same. Furthermore, the internal arrangement of the compacts in vertical disposition affords great 90 convenience to the user, the insertion and withdrawal of the respective puffs assuring the replenishment of cosmetic material thereon without requiring especial effort to 95 be exercised by the user.

Referring now to Figs. 7 to 10 inclusive of the accompanying drawings, I have illustrated therein a somewhat modified construction of my novel vertical double compact container or case, which embodies, however, the basic principles of my invention. In this construction, the reference-character 19 indicates the main body or shell, provided adjacent to the margin of its open end with an annular outwardly projecting bead 20 providing an internal groove 21, that portion of the main body or shell which projects above said bead 20 forming a cover engaging bezel 22. Pivotaly connected with 100 said main body or shell 19, by means of a suitable hinge connection 23, is a cover member 24, within which is arranged a mirror member 25 secured in place by a suitable retaining inlay 26. In this modified construction of case or container, I have not only provided means for supporting the compacts 11 and 12 back to back in the central vertical disposition within the interior 105 of the case, which is the essential principle 110 of my invention, but I have also combined with the means for retaining the compacts in said position additional means providing sockets or holders for other cosmetics, such, for example, as a lip stick 27 and an eye-brow pencil 28. This combined compact and cosmetic retaining means comprises a supporting plate 29 disposed vertically 115 within the main body or shell to extend in a centrally longitudinal direction there- 120

through. The respective ends of said plate 29 are rolled to provide cylindrical or tubular portions 30 forming vertical receiving sockets or holders 31 for the reception and support of said lip stick 27 and said eye-brow pencil 28. In order to hold the said plate 29 in position against displacement I provide the outer portions of the margins of the tubular portions 30, at their upper ends, with lugs 32 which are turned into the internal groove 21 of the body or shell, as shown more clearly in Fig. 8 of the drawings. The compacts 11 and 12 are arranged back to back, one on either side of said supporting plate 29, and the latter is provided at its lower edge with gripping lugs 33 and 34, one of which is turned upwardly over the lower marginal edge portion of the compact 11, and the other of which is turned upwardly over the lower marginal edge portion of the compact 12. An arcuate yoke member 35 is provided for mutual engagement over the upper marginal edge portions of the compacts 11 and 12, the same being anchored or secured against displacement from such holding relation to the compacts 11 and 12, by means of a lug 36 which projects upwardly from the central portion of said plate 29, and through which extends a perforation 37 provided in said yoke-member, said lug being then turned or clenched over in retaining relation to said yoke member. By the above described means it will be apparent that the compacts 11 and 12 are securely retained in the necessary vertical and centrally disposed back to back relation to the interior of the body or shell 19, so that their convex faces are outwardly presented and spaced from the side walls of the body or shell so as to provide puff receiving compartments 38 adjacent to each compact, in which may be inserted the respective puffs 17 and 18, whereby the same are operatively engaged with and related to the respective faces of said compacts 11 and 12.

It will be readily understood from the above description, that the modified structure embodies the general essential features of my invention, so far as the vertical arrangement and disposition of the compacts is concerned, and in addition said structure provides a very convenient means for storing and carrying other cosmetics in stick form.

I am aware that some changes may be made in the general arrangements and combinations of the several devices and parts, as well as in the details of the construction thereof, without departing from the scope of the invention as set forth in the foregoing specification, and as defined in the appended claims. Hence, I do not limit my invention to the exact arrangements and combinations of the said devices and parts as described in said specification, nor do I confine myself to

the exact details of the construction of said parts as illustrated in the accompanying drawings.

I claim:

1. A container for powder and rouge compacts providing a single vertical compartment, means for retaining the compacts in central vertical back to back disposition within said compartment, and spaced from the side walls thereof to provide vertical puff receiving spaces adjacent to each compact. 70

2. A container for powder and rouge compacts, comprising a main body, a cover member hinged to the upper open end of said main body, and means for retaining the compacts in central vertical back to back disposition within said main body and spaced from the side walls thereof to provide vertical puff receiving pockets adjacent to each 80 compact. 85

3. A container for powder and rouge compacts, comprising a main body, a cover member hinged to the upper open end of said main body, means for retaining the compacts in central vertical back to back disposition within said main body and spaced from the side walls thereof to provide vertical puff receiving pockets adjacent to each compact, an arcuate yoke member in embracing relation to the upper marginal edges 90 of said compacts, and means for retaining said yoke member in position. 95

4. A container for powder and rouge compacts, comprising a main body, a cover member hinged to the upper open end of said main body, means for holding said compacts in central vertical back to back disposition within said main body and spaced from the side walls of the latter to provide puff receiving compartments adjacent to each compact, and means for holding said compacts against outward withdrawal from said main body. 100 105

5. A container for powder and rouge compacts, comprising a main body and cover therefor, a vertical supporting plate extending centrally through the interior of said main body, said plate having at its ends vertical tubular portions providing holders for 110 stick cosmetics, means retaining said plate against displacement from said main body, and means for mounting respectively upon the opposite faces of said plate said respective compacts to hold the same in vertical 115 disposition and spaced from the walls of said main body to provide puff receiving compartments adjacent to each compact. 120

6. A container for powder and rouge compacts comprising a main body and cover 125 therefor, a vertical supporting plate extending centrally through the interior of said main body, said plate having at its ends vertical tubular portions providing holders for stick cosmetics, means retaining said plate 130

4
against displacement from said main body, the lower margin of said plate having outwardly and upwardly turned lugs extending in opposite directions to engage the lower 5 edges of said respective compacts to support the latter in vertical positions one on each side of said plate, an arcuate yoke member for mutually engaging the upper edges of said compacts, a clenching lug projecting 10 from said plate upwardly through said yoke member in holding relation thereto, and said

compacts as thus supported being spaced from the walls of said main body to provide vertical puff receiving compartments adjacent to each compact.

In testimony that I claim the invention set forth above I have hereunto set my hand this 10th day of August, 1920.

ROBERT Y. BARROWS.
